UNITED STATES PATENT OFFICE.

LEONARD WALDO, OF PLAINFIELD, NEW JERSEY.

ELECTRIC FURNACE.

No. 833,357.

Specification of Letters Patent.

Patented Oct. 16, 1906.

Application filed June 23, 1905. Serial No. 266,544.

To all whom it may concern:

Be it known that I, LEONARD WALDO, a citizen of the United States, residing in the city of Plainfield, in the county of Union and State of New Jersey, have invented certain new and useful Improvements in Electric Furnaces, of which the following is a specification.

The invention is an electric furnace where-
10 in a charge melted by currents induced in it is also electrolyzed.

Induction-furnaces in which the charge forms a closed secondary circuit wherein current is induced from a primary circuit and the charge thus melted are known. Furnaces in which a charge is both melted and electrolyzed by electrodes in the charge-receiving chamber are known. In the first case there is no electrolysis; in the second, 20 where the same current both fuses and electrolyzes, there is needless waste of energy, because after the charge becomes liquid the current required for electrolysis is relatively small. Nevertheless, an internal current 25 must be maintained sufficient to keep the mass fluid. There is no way of divorcing the heating current from the electrolyzing current in such way as that after fluidity is established the heating current can be dis-
30 pensed with or only used intermittently as occasion may require. Furnaces which first fuse the charge by fuel and then electrolyze it require constant and careful firing. The fire under the crucible must also be kept up
35 during the entire operation.

I have discovered that the difficulties indicated above are completely solved by disposing electrolyzing electrodes in the charge-receiving chamber of an induction-furnace. 40 The induced current may then be used to melt the charge, after which it may be discontinued. The current between the electrodes need only be sufficient to produce the desired electrolysis. Such heat as it con-
45 tributes to the fused mass will delay cooling, so that it will be necessary to establish the inducing-current only intermittently and then for no longer than is necessary to keep the charge at the temperature of fluidity. 50 Both electrolyzing and inducing currents being perfectly controllable independently of one another, it is obvious that both the character and quantity of current flowing can always be adjusted to the particular needs of
55 the operation. The resulting economy is large, for, as well known, a considerable por-

tion of the cost of electrolyzing fused substance is due to the consumption of the electrodes, and this is because of the current they are compelled to deliver in order to effect fusion as well as electrolysis.

It is of course obvious that the electrolyzing current may be operated alternately or simultaneously with the inducing current, as may be desired.

In the accompanying drawings, Figure 1 is a vertical section of a furnace embodying my invention, and Fig. 2 is a section on the line 6 6' thereof.

Referring to the drawings, 1 is the wall of a furnace of any suitable form, but preferably annular, as shown. 2 is the furnace chamber or receptacle to hold the ore, compound, or mixtures to be treated. 3 is the primary windings which are connected with means of supplying an alternating current 7. 4 is the core of soft iron. 5 and 5 are electrodes connected with means of supplying a direct electric current thereto 8. No particular arrangement or form of this combination of 70 elements is necessary except that the furnace-chamber 2 must be of such shape that its contents or some parts thereof will form a closed inductance-circuit, with which is linked the magnetic core-circuit 4, which in 75 turn is linked with the primary alternating circuit 3. The electrodes introducing an electrolyzing circuit 5 and 5 may be adjustable or fixed and may be in any part of the furnace chamber. By any suitable means 80 an alternating electric current is passed through the primary windings 3, setting up magnetic lines of force in the magnetic circuit 4, which in turn induce alternating inductances in the secondary circuit or furnace 85 charge 2, thus heating the same. When the charge has become sufficiently fused, an electrolyzing current, if not already established, is passed between the electrodes 5 and 5 by
90 any suitable means 8.

My invention may be used for a variety of purposes, but is particularly adapted to the reduction and separation of metals from their ores or compounds. If the ores to be treated are sufficiently affected by the alternate in-
95 ductances in their crude state, they may be melted by the ordinary process of the induction-furnace and the fused mass electrolyzed by means of the electrodes, or the melting process may be started by any of the pro-
100 cesses usual with an induction-furnace, such as a ring of metal in the furnace-chamber.

2 The two currents may be controlled independently by any suitable means, as shown in Fig. 2, such as a rheostat 9 inserted in the direct-current electrode-circuit, and a variable inductive resistance 10 in the alternating-current-inducing circuit. The usual circuit-breaking switches 11 12 in the respective circuits may also be introduced.

I claim—

- 10 1. In an induction-furnace, having a charge-receiving chamber and an inducing-circuit for melting the charge in said chamber, means for electrolyzing said melted charge.
- 15 2. In an induction-furnace, having a charge-receiving chamber and an inducing-circuit for melting the charge in said chamber, means for electrolyzing said melted charge, means for controlling the electrolyz-

ing current and means for controlling the 20 inducing current.

3. In an induction-furnace, having a charge-receiving chamber and an inducing-circuit for melting the charge in said chamber, electrodes disposed in said chamber. 25

4. In an induction-furnace, having a charge-receiving chamber and an inducing-circuit for melting the charge, electrodes disposed in said chamber and a source of direct current in said circuit with said electrodes. 30

In witness whereof I have hereunto signed my name in the presence of two subscribing witnesses.

LEONARD WALDO.
